(No Model.)

A. HARLEY.

RAILROAD SWITCH.

No. 254,008.

Patented Feb. 21, 1882.

UNITED STATES PATENT OFFICE.

ARCHIBALD HARLEY, OF TOPEKA, KANSAS.

RAILROAD-SWITCH.

SPECIFICATION forming part of Letters Patent No. 254,008, dated February 21, 1882.

Application filed December 15, 1881. (No model.)

To all whom it may concern:

Be it known that I, ARCHIBALD HARLEY, a citizen of the United States, residing at Topeka, in the county of Shawnee and State of Kansas, have invented new and useful Improvements in Railroad-Switches, of which the following is a specification.

My improvement in railroad-switch levers consists, first, in the combination, with the switch-rod, of a vertical swinging jointed switch-lever, pivoted at its lower or inner end, the upper part of said jointed switch-lever being adapted to be swung down and secured to a supporting-standard of the apparatus after the lower part of the switch-lever has been brought into a vertical position; second, in the combination, in a railroad switch-stand, of the vibratory jointed switch-lever for operating the switch-rod with the standards between which the switch-rod is pivoted, one of these standards having its upper end formed with a mortise to receive the upper part of the switch-lever when said part is swung down to a horizontal position, suitable openings being formed through the switch-lever and the mortised standard for receiving a locking-pin; third, in the combination, in a railroad-switch stand, of two standards with a jointed switch-lever pivoted between them, upright arms secured at the sides of the apparatus for engaging the switch-lever when it is turned down to the right or to the left, a jointed locking-pin for securing the switch-lever in either of the three positions hereinafter described, and a padlock for engaging the locking-pin.

In the drawings, Figure 1 is a perspective view of the apparatus with the switch-lever turned down and locked. Fig. 2 is a side elevation with the switch-lever raised and locked. Fig. 3 is a transverse section of Fig. 2, taken on a vertical plane.

The support for the fulcrum-pin of the switch-lever consists in the present instance of two standards, A A, that are formed or provided with base-flanges a, and rigidly secured to a cross-tie or other suitable foundation by means of bolts or spikes passing through or otherwise applied to said base-flanges. These standards are arranged at a suitable distance apart, so as to leave a space between them for the switch-lever, which is composed of two parts, B and

B', jointed together by a pivot, b. The upper part, B', of this jointed switch-lever forms a convenient handle for the switchman to take hold of, and upon an end of the fulcrum-pin 55 B² of the lower part of the switch-lever, extending out from one of the standards, is secured a crank-arm, C, carrying at its outer end a wrist-pin. The switch-rod D connects with this wrist-pin, so that when the switch-lever is 60 operated by the switchman the fulcrum-pin, which is in rigid connection with said lever, will rotate about its axis, and thus turn the crank-arm and move the switch-rod so as to shift the switch up to or away from the main 65 track, as the case may be.

I have made provision in this apparatus for holding and locking the switch-rod and switch in three distinct positions. This is accomplished by the following means: When the 70 switch-lever is turned so as to bring it into a vertical position between the two standards the upper part of said lever can be swung downward into a mortise, E, that is formed in the upper end of one of the standards. When said 75 upper part of the switch-lever is thus rested horizontally in the seat or mortise of the standard the inner end of said part of the lever will project to some extent out from the mortise, which is at the joint of the two parts of the 80 switch-lever. To provide room for this projecting inner end of part B' of the switch-lever, and at the same time to render the apparatus as compact as possible, I form in the inner side of one of the standards a recess, F, which receives the said projecting end of the lever when the part B' is swung down into a horizontal position, just described. To now hold the switch-lever in place I pass a jointed locking-pin, G, through holes in the switch-lever and the mortised upper end of the standard, and to secure the jointed locking-pin so that it cannot be accidentally or surreptitiously removed I provide a padlock, H, which can be locked onto the perforated point of the locking-pin. In 90 this way the head at one end and the padlock at the other end of the locking-pin prevent the withdrawal of the same from the switch-lever and standard. To prevent the padlock and the pin from being lost or taken away I can connect them by chains with one of the standards.

The switch and the switch-rod are brought into

either of two other positions, lifting the outer end of the switch-lever from the mortise in the standard, and thereby straightening out the switch-lever, and then swinging the same down 5 to the right or the left of the standards. When the inner part, B, of the switch lever is thus swung down to a horizontal position the crank-arm upon its fulcrum-pin will be brought into a like position, and to hold the switch-lever 10 down I provide the curved upright arms I I, located at the opposite sides of the fulcrum-pin of the switch-lever.

A mortise, K, is formed through the inner part of the switch-lever, of sufficient size to receive either of the upright arms I when the lever is swung down in the manner last described. The upper end of each one of these arms has a 15 perforation for the passage of the locking-pin, so that when the switch-lever is turned down 20 by the switchman to the right or to the left one of the arms will pass through the mortise of the lever and project up above the same, so that the locking-pin can be passed through the perforation of the arm, and thereby hold the lever down. The padlock can then be applied to 25 the locking-pin, as before described.

By the above construction and arrangement of parts a positive movement of the switch-rod is effected without any lost motion. 30 The base-rests for the switch-lever when it is turned down to the right or the left, the mortise or seat in the upper end of one of the standards, and the throw of the crank-arm are all so arranged that when the switch-lever is 35 brought into position for switching the several rails will properly match.

Instead of forming the standards separately, it is obvious that they could be united at their lower ends by a common flange or base-plate; 40 and it will also be obvious that in lieu of employing a pivot for connecting the two parts of the switch-lever together, an ordinary leaf-hinge could be used for such purpose.

The outer end of an arm that may be applied to one end, b', of the fulcrum-pin B², can 45 be provided with any appropriate signal, so that the engineer of an approaching train can readily determine the position of the switch.

Prior to this invention a railroad-switch 50 mechanism has been provided with a vertical shaft arranged to rotate about its axis and operated to move the switch tracks or rails that are connected by a rod or bar with a crank upon the lower end of said shaft by 55 means of jointed horizontal handle having its outer weighted end adapted to be dropped into grooves formed in an elevated support or table; but in my apparatus the jointed lever is mounted upon its lower end upon a short horizontal shaft or pivot, which occupies but little 60 space, and in swinging the jointed lever in

a vertical plane I am enabled to obtain greater leverage than if the handle were connected with a vertical rotary shaft, unless the handle attached to said vertical shaft were made quite 65 long, which would be objectionable. In another instance a single lever has been pivoted at its lower end and a hook arranged upon the base of the apparatus in position to engage with a spring-catch carried by the swinging 70 lever. Such device, however, lacks the feature of the jointed lever and the means hereinbefore described for engaging the outer section of the lever when its inner section is in a vertical position, and means for engaging the 75 lower or inner section of the jointed lever when said lower or inner section has been swung down.

Having thus described my invention, what I claim is—

1. The combination, in a railroad-switch, of the switch-rod with a vertically-swinging jointed switch-lever, pivoted at the inner end of its lower section, the upper part of said jointed switch-lever being adapted to be swung down 85 and secured to a supporting-standard of the apparatus after the lower part of said lever has been brought into a vertical position, substantially as described.

2. The combination, in a railroad-switch, of 90 the vibratory jointed switch-lever for operating the switch-rod with the standards between which the switch-lever is pivoted, one of these standards having its upper end formed with a mortise to secure the upper part of the switch-lever when said part is swung down to a horizontal position, suitable openings being formed 95 through the switch-lever and the mortised standard for receiving the locking-pin, substantially as and for the purpose described.

3. The combination, in a railroad-switch, of the standards A with the jointed switch-lever pivoted between said standards, the arms I, the jointed locking-pin, and the padlock, the upper part of the jointed switch-lever being 105 adapted to be secured by the locking-pin in a mortise in one of the standards when the lower part of said lever is brought into a vertical position, and the arms I being each adapted to receive the locking-pin, so that after the 110 switch-lever has been turned down and either arm received in the mortise of the switch-lever the pin can be engaged with the arm and secured by the padlock, substantially as described.

In testimony whereof I have hereunto set my hand in the presence of two subscribing witnesses.

ARCHIBALD HARLEY.
